US00D918040S

(12) **United States Design Patent** (10) **Patent No.:** **US D918,040 S**
Blomberg et al. (45) **Date of Patent:** **** May 4, 2021**

(54) **ACCESS-RESISTANT JAR**

(71) Applicant: **POLLEN GEAR LLC**, Hermosa Beach, CA (US)

(72) Inventors: **Shane Grant Blomberg**, Hermosa Beach, CA (US); **Edward Kilduff**, Hermosa Beach, CA (US)

(73) Assignee: **POLLEN GEAR LLC**, Hermosa Beach, CA (US)

(**) Term: **15 Years**

(21) Appl. No.: **29/670,346**

(22) Filed: **Nov. 15, 2018**

Related U.S. Application Data

(63) Continuation-in-part of application No. 29/589,016, filed on Dec. 27, 2016, now Pat. No. Des. 842,700, which is a continuation-in-part of application No. 29/580,322, filed on Oct. 7, 2016, now abandoned.

(57) **CLAIM**

The ornamental design for an access-resistant jar, as shown and described.

DESCRIPTION

FIG. 1 is a top perspective view of an access-resistant jar in a closed condition in accordance with the present teachings. FIG. 2 is a bottom perspective view of the access-resistant jar of FIG. 1.

FIG. 3 is a side view of the access-resistant jar of FIG. 1. FIG. 4 is a top view of the access-resistant jar of FIG. 1; and, FIG. 5 is a bottom view of the access-resistant jar of FIG. 1. The access-resistant jar is transparent with an opaque closure. The inside and opposing side details seen through the transparent sidewall material of the jar have been omitted from FIGS. 2 and 5 for ease of understanding.
